ALBERT HENRY MIDGLEY, OF ACTON VALE, ENGLAND, ASSIGNOR OF ONE-HALF TO
C. A. VANDERVELL AND COMPANY LIMITED, OF ACTON VALE, ENGLAND.

ELECTRIC STARTER FOR INTERNAL-COMBUSTION ENGINES.

1,254,923.

Specification of Letters Patent. Patented Jan. 29, 1918.

Application filed July 19, 1917. Serial No. 181,643.

To all whom it may concern:

Be it known that I, ALBERT HENRY MIDGLEY, a subject of the King of Great Britain and Ireland, and residing at Warple 5 Way, Acton Vale, in the county of Middlesex, England, have invented certain new and useful Improvements in and Relating to Electric Starters for Internal-Combustion Engines, of which the following is a specification.

This invention relates to an improved electric starter for internal combustion engines of the kind wherein the initial engagement of the gear members is effected by 15 a longitudinal movement of the armature shaft under magnetic action and the completion of the engagement by means of a screw or helical connection between the longitudinally movable armature shaft and the 20 member of the gear carried by the latter, such as described in British patent specification No. 24293 of 1914.

In starters of the kind above referred to, the longitudinal movement of the armature shaft is substantially reduced as compared with the longitudinal movement of the shaft in starters which are not provided with a screw or helical device and wherein the one member of the gear is fixed to said shaft, 25 and one object of the present invention is to further reduce the longitudinal movement of the shaft, another object being to improve the initial stage of operation of the starting device.

35. With these objects in view the invention consists in causing a friction disk or equivalent member used in conjunction with the pinion which is connected with the longitudinally movable armature shaft through 40 the screw or helical device to be brought into frictional contact with the fly-wheel of the engine or other rotary or stationary member under slow rotation of the electric motor and by a very short longitudinal 45 movement of its armature shaft, prior to the initial engagement of the toothed members of the gear, which latter engagement is subsequently effected and completed by the screw or helical device in a known manner.

50. The friction disk or equivalent member may either be attached to the pinion or arranged to rotate therewith, while being capable of moving longitudinally relatively thereto, as has already been proposed in electric starters wherein an ordinary motor

is employed, the shaft of which is connected with the pinion by means of a screw or helical device but is not longitudinally movable as in the arrangement according to the present invention and wherein the friction device comes into operation before the initial engagement of the gear members in order to assist the effect of the inertia of the pinion and thereby insure its operation and more particularly its engagement with the other 60 member of the gear. The arrangement according to the present invention differs from these forms of construction which have previously been proposed in that the short longitudinal movement of the shaft under slow 65 rotation is employed for initiating the operation of the starter, and not the inertia of the pinion and friction disk which is dependent upon a rapid acceleration of the electric motor as is the case in the known 70 forms of construction.

Referring to the accompanying drawing which illustrates by way of example one mode of carrying the invention into effect, *a* is the electric motor, *b* its longitudinally 75 displaceable armature shaft, *c* a helically threaded member suitably keyed to the armature shaft, and *d* is a pinion which is mounted in helical engagement with the helically threaded member *c* and is adapted to coöperate with a toothed ring *e* provided on the fly-wheel of the engine to be started or on other rotary member connected or coöperating therewith.

f is a friction ring mounted on a cover *g* which is loosely supported on the longitudinally movable armature shaft *b* in such a manner as positively to follow the longitudinal displacement of the latter in one or the other direction and thereby be brought into frictional engagement with the side of the toothed ring *e* or other rotary or stationary part of the engine. The pinion *d* is provided with a guiding pin *h* arranged slidably to engage with the cover *g*. *i* is a spring interposed between a stationary part of the electric motor and an abutment *j* on the armature shaft and arranged to act in a well known manner during the inward longitudinal movement of the shaft and for causing the outward displacement thereof.

Instead of mounting the friction ring *f* on a member *g*—forming a cover for the pinion *d* as has previously been proposed—the same may otherwise be loosely supported on the 110

longitudinally movable shaft in such a manner that it shall follow the longitudinal displacement thereof, and the details of construction of the starter hereinbefore described may otherwise be modified without in any way departing from the spirit of the invention.

What I claim is:—

An electric starter for internal combustion engines comprising in combination an electric motor having an armature shaft capable of longitudinal displacement, a toothed gear, one member of which is connected with the engine to be started while the other member thereof consists of a helically threaded pinion, a helical thread on the longitudinally displaceable armature shaft in engagement with the helically

threaded pinion, and a friction device constituted by two members, one of which is supported on the longitudinally displaceable shaft so as to be capable of relative rotation thereon, together with the helically threaded pinion, and be compelled positively to follow the longitudinal displacement of the armature shaft, the distance between the members of the friction device being shorter than the distance between the members of the toothed gear, whereby the friction device is brought into operation during the longitudinal displacement of the armature shaft and before the initial engagement of the members of the toothed gear, as set forth.

In testimony whereof I have signed my name to this specification.

ALBERT HENRY MIDGLEY.
